W. HILTON

FILE GAUGE

Filed March 30, 1925

INVENTOR
William Hilton
BY
Harry Bowen
ATTORNEY

UNITED STATES PATENT OFFICE.

WILLIAM HILTON, OF SEATTLE, WASHINGTON.

FILE GAUGE.

Application filed March 30, 1925. Serial No. 19,516.

To all whom it may concern:

Be it known that I, WILLIAM HILTON, a subject of the King of England, residing at Seattle, county of King, and State of Washington, have invented a new and useful Improvement in File Gauges; and I do hereby declare that the following is a full, clear, and exact specification, such as will enable others skilled in the art to which it appertains to 10 make and use the same.

The invention is an improvement in file gauges in that a means is provided for gripping the saw.

The invention is an improvement over my 15 prior Patent No. 1,521,098, issued December 30th, 1924, and also my prior application which was filed August 6th, 1923, with the Serial Number 664,314.

The object of the invention is to provide 20 a simple and efficient means for rigidly clamping the gauge on a saw or the like.

With these ends in view, the invention embodies slideable side plates at the sides of the block, a cam shaped member for clamping 25 the side plates toward one end, a spring for drawing the side plates toward the opposite end and a rigid member for holding the gauge or spacer that co-operates with the side plates to hold the saw at proper intervals. 30

Other features and advantages of the invention will be seen from the following description taken in connection with the drawings, wherein:—

Figure 1 is a side elevation.

Figure 2 is a plan view.

Figure 3 is a sectional view on line 3—3 of Figure 1.

Figure 4 is a section similar to that shown 40 in Figure 3 showing an alternate means for clamping a bracket to the block.

Figure 5 is a sectional view showing a side view of the clamp shown in Figure 4.

Figure 6 is a view showing the gauge for 45 holding the saw teeth at regular intervals.

Figure 7 is a view showing another alternate arrangement for holding the bracket to the block.

Figure 8 is a view showing an alternate 50 arrangement for holding the file.

Figure 9 is a similar view showing another alternate design.

Figure 10 is a view showing a clamp of

an alternate design for holding a flat file in the device. 55

In the drawings I have shown my file gauge as it would appear wherein numeral 1 indicates the block, numeral 2 the bracket, and numeral 3 the file carriage.

The block 1 is made of a piece of sheet metal or any other suitable material and made in the form of a rectangular shaped shell with one end wider than the other and one side open. The interior is filled with a block, which may be of wood or any suitable material, which has a straight cut through its center as indicated by the lines 4 which show the position of a rip saw over which the block may be placed while it is being filed; and diagonal cuts through it as 60 indicated by the dotted lines 5 and 6 through which cross cut saws may be placed while being filed. In the metallic sides are slots 7, which have enlarged openings 8 at their upper ends and beveled surfaces 9 at the 65 lower edge of the openings which should have a slope similar to that of the saw teeth. The slots 7 are placed at the ends of the cuts 4, 5 and 6 so that the saw will pass through them. 70

At the sides of the block are gauges 10 which engage the teeth of the saw and hold it while it is being filed. The gauges 10 are made of flat pieces of material with beveled edges 11 and 12 which engage the saw teeth, 85 and projections 13 and 14 which may be bent around a groove 15 in the head of a screw 16 which may be screwed into a hole between the enlarged portions 8 of two of the slots 7 so that as they are turned on 90 one side of the screw they will engage the teeth of the saw that may be placed in the center slot and when they are turned on the opposite side they will engage a saw placed through one of the diagonal slots. 95

The bracket 2 may be constructed with flat pieces of material 17 bent as shown in Figure 1 and having openings 18 in enlarged sections 19 at the ends by which the bracket may be held to the block. The ends 100 are held by thumb screws 20 that may be placed through the openings 18 and screwed into the ends of the block or into nuts, lugs, or enlarged portions on the insides of the ends as may be desired. The upper ends 21 105 of the flat pieces of material 17 are provided

with holes into which a bar 22 having a guide bar 23 may be placed. The saw carriage 3 is slidably mounted on the bar 22 through a sleeve 24 upon which the hubs 25 of the arms 26 are rigidly held by set screws 27. Projections 28 with recesses 29 in them will extend outward from the arms 26 and the recesses 29 of these projections will engage the guide bar 23 when the carriage is in the filing position. The file which I have indicated by the numeral 30 may be held in sleeves 31 having triangular shaped openings 32 in them and these sleeves are held in openings in hubs 33 at the outer ends of the arms 26 by set screws 34. It will be seen that by moving the handle 35 on the end of the file backward and forward the file carriage will slide backward and forward on the rod 22, and by swinging the carriage over to the opposite side of the block it will be possible to obtain the same movement and file the saw on that side.

Figures 4 and 5 show an alternate means for clamping the bracket 2 to the block in which the ends of the flat pieces of material 17 are split and bent downward, forming flanges which may be clamped to the ends of the block by screws 36 passing through pins 37 in the flanges. It will be seen that by loosening the screws 36 it will be possible to twist the bracket to any desired angle in relation to the block.

The enlarged sections 19 of the flat pieces of material 17 may be provided with points 38 as shown in Figure 3 which may be set opposite graduation marks 39 on the ends of the block so that it will be possible to set the file bracket at any given angle.

In the design shown in Figure 7 the ends of the bracket 17 are provided with slots 40 through which the thumb screws 36 in the slots 41 may pass. It will be seen that as the thumb screws are tightened they will hold the brackets 17 against the ends of the block and by adjusting the screws it will be possible to hold the brackets in any desired position.

The block may be provided with side plates 42 which are supported at the sides of the block on screws 43 in slots 44 as shown in Figure 1. In the sides of the plates 42 are openings 45 to correspond with the openings 8 and slots 7 in the block and extension 46 at the ends to which levers 47 with cams 48 in their ends are pivoted. It will be seen that as a saw is placed through one of the openings the lever 47 may be drawn upward which will cause the cams 48 to draw the plates toward the end of the block, that the saw will be clamped in the opening at both sides. At the opposite end of the block, the plates 42 are provided with extensions 49 having openings 15 in them through which the ends of a spring 51 will project as shown in Figures 1 and 2 and it

will be observed that as the plates are released by the cam at the opposite end or by moving the lever 47 downward, the spring will draw the plates backward or toward the large end of the block.

In the design shown, the screws 16 are threaded into a threaded tubular shaped bar 52, as shown in Figure 2 so that the gauge 10 may be positively held.

In Figure 8, the arms 22 are bent around as shown and are provided with screws 53 by which the sleeves 31 may be clamped in the ends of the arms; and in the design shown in Figure 9, the outer ends of the arms 26 are split and provided with a bolt 54 by which they may be drawn together to clamp the sleeves 31.

In Figure 10 I have shown a means for holding a flat file which comprises a split jaw with a tapering shank 55 and a washer 56 on it which may be moved downward toward the jaws which I have indicated by the numerals 57 and 58. It will be seen that a file 60 may be placed between the jaws and the washer 56 moved downward until the jaws grip the file. The tapering shank 55 may then be placed in the hub 33 and held in place by the set screw 60.

It will be understood that changes may be made in the construction without departing from the spirit of the invention. One of which changes may be in the design of the block, as it is understood that this may be made square or of any desired shape; another may be in the shape of the slots through the block; another may be in the design of the brackets or in the means for holding them to the block; and still another may be in the design of the carriage for holding the file.

The construction will be readily understood from the foregoing description. To use the device it may be assembled as shown and the block 1 placed over the saw as shown in Figures 2 and 3 and it will be seen that the brackets may be adjusted so that the file will rest between the saw teeth. It will also be seen that by moving the saw backward or forward and setting the gauge 10 between two of the teeth, it will be possible to hold the saw at regular intervals or in such positions that each or every other tooth may be filed without resetting the gauge. The sleeves 31 in the file carriage will make it possible to remove and replace a file as often as may be desired. It will also be observed that the end slots 7 may be made diagonal as shown in Figure 1 in dotted lines so that the vise may be placed on a cross cut saw to file it.

Having thus fully described the invention, what I claim as new and desire to secure by Letters Patent, is:—

1. In a file gauge of the class described a saw holding base, slotted plates on the

sides of the said saw holding base, a cam shaped lever for holding the plates toward one end and a means for resiliently holding the plates toward the opposite end.

5. 2. In a file gauge of the class described a block having slots through it that may be placed over the device to be filed, means at

the sides of the block for locking the device to be filed in the block, means for resiliently releasing said locking means, other means at 10 the sides of the block for engaging the device to be filed at regular intervals, and other means for slidably supporting a file.

WILLIAM HILTON.
